DESIGN FOR A COMBINATION PICTURE EXHIBITING STAND AND ASH TRAY

William C. Landon, Washington, D. C., and
George A. Myers, Bethesda, Md.; said Myers
assignor to said Landon

Application November 18, 1943, Serial No. 111,720

Term of patent 3½ years

To all whom it may concern:

Be it known that we, William C. Landon and George A. Myers, citizens of the United States of America, residing, respectively, at Washington, D. C., and Bethesda, in the county of Montgomery and State of Maryland, have invented a new, original, and ornamental Design for Combination Picture Exhibiting Stand and Ash Tray, of which the following is a specification, reference being had to the accompanying drawing, forming part thereof, in which,

Figure 1 is a front elevational view of the combination picture exhibiting stand and ash tray; and

Fig. 2 is a top plan view thereof.

We claim:

The ornamental design for a combination picture exhibiting stand and ash tray as shown.

WILLIAM C. LANDON.
GEORGE A. MYERS.
